UNITED STATES PATENT OFFICE.

JAMES WESLEY BROWN, OF LOS ANGELES, CALIFORNIA.

TRUCK BODY.

Application filed October 20, 1924. Serial No. 744,669.

In this specification, and the accompanying drawing, I shall describe and show a preferred form of my invention, and specifically mention certain of its more important objects. I do not limit myself to the forms disclosed, since various changes and adaptations may be made therein without departing from the essence of my invention as hereinafter claimed; and objects and advantages, other than those specifically mentioned, are included within its scope.

My invention relates to vehicle bodies adapted for transporting freight and merchandise, and among its principal objects are; first, to provide a truck body having sectional sides and ends that may be variably removed, or latched together to form a virtually continuous enclosure; second, to furnish facilities for swinging certain sections of the sides horizontally outward for use as loading bridges, without removing them from the body; and, third, to make it possible to swing such side sections outwardly and downwardly to a vertical position, without removing them from the body.

Still further objects are: to provide unusually rigid attaching means for the removable side and end sections; and to accomplish the stated purposes by means of very simple and relatively inexpensive construction.

My objects have been attained in the manner illustrated in the accompanying drawings, in which—

Figure 1 is a side elevational view of a truck body of my improved construction;

Figure 2 is rear end elevation of the same;

Figure 3 is a plan view of the body with one of the rear enclosing sections removed;

Figures 4, 5, and 6, respectively are enlarged cross sections in elevation of a removable hinged side section in upright, horizontal and hanging positions;

Figure 7 is a still further enlarged cross-sectional elevation of the hinged portion of the swinging side sections, illustrating further details of the construction; and

Figure 8 is a side elevation of the construction shown in Fig. 7.

Similar reference numerals refer to similar parts throughout the several views.

Before passing to a detailed description of the construction, attention is called to the fact that general utility trucks, such as my invention comprises, are obliged to handle a great variety of sizes and kinds of freight under diverse conditions. This makes it

necessary to have the sides and rear end completely removable, and it is also desirable to sectionize the sides and ends so that they may be partially removed. There are many times when it is impossible for the vehicle to closely approach a loading platform, and in such cases the ability to swing a side section horizontally outward for use as a loading bridge is a great advantage. In other cases it is desirable to be able to swing a side section outwardly and let it depend vertically from the body without removal therefrom. For all these purposes my construction is well adapted.

In the embodiment of my invention selected for illustrative purposes I have shown a platform 9 having a continuous steel band 10 around its edge, and three-sided metal boxes 11 spaced around the periphery to constitute four sided stake pockets in cooperation with the band. The walls 12 of the boxes opposed the band are parallel thereto, and the other two walls 13 converge downwardly. Rigid side and end sections, such as 14 and 15 respectively, are provided with continuous solid stakes 16. Swinging side sections 17 are provided with hinged stakes 18. All stakes, both solid and hinged, have their lower ends tapered to fit the stake pockets.

The hinged stakes comprise an upper and lower portion having specially shaped opposed metal ends 19, into which the stake portions are socketed and fastened by rivets 20. The metal ends are spaced by an amount approximately equal to the thickness of band 10, and are joined by a thick link 21 that is free to turn upon rivet pins 22. This construction is shown most clearly in Figs. 7 and 8. The proportions and dimensions of the co-operating parts are such that, when the hinged stakes are in place in their pockets, the hinged joint is about central therein and becomes in-operative. When slightly raised the stakes may be swung outwardly and permit the side sections to assume either of the positions shown in Figs. 5 and 6. In either of these positions the link 21 rests upon band 10 and supports the outwardly swung side section. In Fig. 5 the section is used as a loading bridge with one end supported in the manner just described, and the other end resting upon a loading platform 23.

I prefer to construct my bodies with a gate 24 at each side of driver's cab 25. This per-

units of loading long merchandise, such as pipe or lumber, when the corresponding rear section is removed as shown in Fig. 3. I also prefer to provide suitable latches 26 whereby all of the side and end sections may be connected together near the top. A panel 27 may be utilized for display purposes.

A further important feature of my invention is the use of a longitudinal member, as 10 the angle iron 28, for resisting the lateral thrust of the lower ends of the solid stakes. This angle iron is attached beneath the outer ends of cross sills 29, as shown most clearly in Figs. 1 and 2. Its use greatly increases 15 the purchase of the stakes and minimizes the effect of wear of the stakes in the sockets. In the case of the hinged stakes the longitudinal member is of no utility and socket-wear of the hinged stakes is reduced and 20 minimized by the metal ends at the hinged joints.

Having thus fully described my invention, I claim:

1. A truck body comprising removable 25 side sections with downwardly extending stakes having lower portions pivotally connected to the upper portions beneath the lowermost edge of the side boards; said body having stake pockets adapted to embrace 30 the pivoted portions of said stakes.

2. A truck body comprising removable 35 side sections with downwardly extending stakes having lower portions link-connected to the upper portions beneath the lowermost edge of the side boards; said body having stake pockets adapted to embrace the link-connected 40 portions of said stakes.

3. A truck body comprising removable 45 side sections with downwardly extending stakes having lower portions slightly spaced from the upper portions and link-connected thereto beneath the lowermost edge of the side boards; said body having stake pockets

adapted to embrace the link-connected portion of said stakes.

4. A truck body comprising removable 45 side sections with downwardly extending stakes having lower portions slightly spaced from the upper portions and link-connected thereto beneath the lowermost edge of the 50 side boards; said body having stake pockets at the edge of its deck adapted to embrace the link-connected portion of said stakes; and said link-connections being adapted to permit the side sections, after being slightly 55 raised, to swing outwardly and be supported by said links resting upon the outer edges of said stake pockets.

5. A truck body comprising removable 60 side sections with downwardly extending stakes having lower portions slightly spaced from the upper portions and link-connected thereto beneath the lowermost edge of the side boards; said body having stake pockets at the edge of its deck adapted to embrace 65 the link-connected portions of said stakes; and said link-connections being adapted to permit the side sections, after being slightly raised without removing the lower portions of the stakes from the stake pockets, to 70 swing outwardly and downwardly to a vertical position and be supported by said links resting upon the outer edges of said stake pockets.

6. A truck body comprising; a platform 75 with a metal edge and downwardly tapered stake pockets adjacent thereto; and removable taper-staked side sections having spaced extremities at the lower ends of the stakes, link-connected thereto; said stakes being 80 adapted for being normally held upright in said pockets and for being swung outwardly when slightly raised from normal position to an inverted position depending from said edge with said link supported thereby.

JAMES WESLEY BROWN.
